United States Patent Office

Des. 196,288
Patented Sept. 10, 1963

196,288

MASTICATORY EXERCISER

Rafael C. Jané, 81 Cottage St., Whitinsville, Mass.

Filed Oct. 2, 1962, Ser. No. 71,976

Term of patent 14 years

(Cl. D83—1)

The FIGURE is a perspective view of a masticatory exerciser, showing my new design.

The undisclosed side is a mirror image of the side shown.

I claim:

The ornamental design for a masticatory exerciser, as shown and described.
